UNITED STATES PATENT OFFICE.

DELBERT E. LANE, OF CHICAGO, ILLINOIS.

INTERNAL-COMBUSTION ENGINE.

1,097,032.

Specification of Letters Patent. Patented May 19, 1914.

Application filed May 7, 1913. Serial No. 766,027.

To all whom it may concern:

Be it known that I, DELBERT E. LANE, a citizen of the United States of America, and a resident of Chicago, county of Cook, and 5 State of Illinois, have invented certain new and useful Improvements in Internal-Combustion Engines, of which the following is a specification.

The main objects of this invention are to 10 provide an improved form of internal combustion engines of the two-cycle type; to provide an improved arrangement of the ports and passages connecting the pumping and engine cylinders with each other and 15 with the fuel inlet and the exhaust; and to provide an improved construction of the engine and pumping pistons whereby they are adapted to control communication between 20 said ports, passages, and cylinders.

An illustrative embodiment of this invention is shown in the accompanying drawings in which:

Figure 1 is a sectional elevation of one unit of an internal combustion engine of 25 this kind. Fig. 2 is a side elevation of the same. Fig. 3 is a diagrammatic sectional view showing the relative positions of the pistons at the time that ignition takes place. Fig. 4 diagrammatically illustrates the relative 30 angular positions of the crank pins corresponding to the positions of the pistons shown in Fig. 3. Fig. 5 is a sectional elevation showing the relative positions of the pistons during expansion in the engine cylinder and intake of fuel into the pumping cylinder. Fig. 6 diagrammatically illustrates the angular positions of the crank pins corresponding to Fig. 5. Fig. 7 is a 35 sectional elevation but showing the relative positions of the pistons during the exhaust from the engine cylinder and compression of fuel in the pumping cylinder. Fig. 8 illustrates the angular positions of the crank pins corresponding to Fig. 7. Fig. 9 is a 40 sectional elevation showing the relative positions of the pistons during the intake and compression of fuel in the engine cylinder. Fig. 10 illustrates the angular positions of the crank pins corresponding to Fig. 9.

In the construction shown in the drawings, the casting 1 is constructed to form an engine cylinder 2 having a chamber 3, and a pumping cylinder 4 having a chamber 5. Pistons 6 and 7 are operatively arranged in 45 the respective cylinders 2 and 4 and connected by connecting rods 8 and 9 to the crank

shaft 10 journaled in the bearings 11 of the crank casing 12. The dividing wall 13, separating the two cylinders, is provided with a plurality of communicating ports 60 hereinafter respectively designated as the lower port 14, upper port 15, and intermediate port 16. Communication between the cylinders is afforded by means of these ports which are controlled by the pistons 6 and 7. 65 A fuel inlet port 17 is located near the lower left hand side of the engine cylinder 2 substantially level with the lower communicating port 14. An exhaust port 18 is located at the upper right hand side of the pumping cylinder 4 substantially level with the upper communicating port 15. A carburetor (not shown) may be connected to the inlet port 17, and an exhaust pipe (not shown) may be connected to the exhaust 70 port 18.

The engine piston 6 is provided with upper and lower recesses 19 and 20, which are adapted to respectively register with the communicating ports 14 and 16 at different 80 times during certain periods of the movement of the piston 6. A passage 21 extends upwardly through the piston from the recess 20 to the end of the piston and opens into the chamber 3. The pumping piston 7 is 85 also provided with upper and lower recesses 22 and 23, which at different times during certain periods of the movement of the piston are respectively adapted to register with the communicating ports 14 and 16, and the 90 exhaust port 18, and communicating port 15. A passage 24 extends from the lower recess 22 upwardly through the piston 7 to the end thereof, and opens into the chamber 5. The recesses 19, 20, 22, and 23 extend 95 entirely around the pistons, so that the gas pressure will not cause uneven bearing of the pistons against the cylinder walls. The crank shaft 10 is provided with crank pins 25 and 26, for the rods 8 and 9, which pins 100 are spaced apart angularly, as indicated in Fig. 2, with the pump crank pin in advance. The engine cylinder 2 is shown provided with the usual water-jacket 27 and a spark plug 28.

The operation of the device shown is as follows: The crank shaft 10 revolves in the direction of the arrow 29 (Fig. 2) and intake, compression, expansion, and exhaust will occur in succession during every complete revolution of the crank shaft 10. The 105 relative positions of the pistons when igni-

tion occurs is shown in Fig. 3. During the expansion of the ignited gases both pistons are moving downward, the pumping piston slightly in advance of the engine piston.

5 The recesses 19 and 22 simultaneously come into registration with the fuel inlet port 17 and communicating port 14, and in view of the fact that the pumping piston 7 is moving downward fuel is drawn into the chamber 5 through the inlet port 17, recess 19, port 14, recess 22, and passage 24. The relative positions of the pistons during the early part of the intake are shown in Fig. 5. The intake of fuel continues so long as the recesses 19 and 22 both remain in registration with the port 14. The recess 22 remains in registration with the port 14 during the remainder of the down-stroke of its respective piston and during an early part of the 20 upstroke. However, communication between the inlet port and the chamber 5 is cut off when the recess 19 in the piston 6 moves below the ports 17 and 14. During this early part of the return stroke of the piston 25 7, the piston 6 is caused to keep the ports 14 and 17 closed until the piston 7 has traversed a sufficient portion of its return stroke to move the recess 22 out of registration with the port 14. As the piston 6 approaches the 30 lower limit of its movement its upper end uncovers the port 15 and allows the escape of the burned gases through said port into the recess 23. The uncovering of the port 15 occurs just after the piston 7 begins its 35 return movement, and as the recess 23 moves into registration with the ports 15 and 18. The burned gases are, therefore, allowed to escape through the exhaust port 18. The relative positions of the pistons during exhaust are shown in Fig. 7. At the time that the engine piston 6 completes its stroke, the pumping piston has already moved upwardly, closing the port 14 and causing compression of the gases in the chamber 5, and 40 45 as the engine piston 6 begins to cover the port 15 on the return stroke the recesses 20 and 22 move into registration with the intermediate port 16 so that there is admission of fuel from the pumping cylinder 4 into the engine cylinder 3 before the port 15 is completely closed. This is timed to cause proper scavenging of chamber 3. Fig. 5 shows the piston positions when scavenging takes place. As the pistons continue 50 55 their upward movements the fuel is forced from the chamber 5 through the passage 24, recess 22, port 16, recess 20, and passage 21 into the chamber 3, where it is further compressed during the return movement of the 60 piston 6. By virtue of the angular relation of the crank pins 25 and 26, the piston 7 completes its return stroke first and thereby forces practically all the gaseous fuel out of the cylinder 4 into the engine cylinder 2 before the engine piston 6 completes its com-

pression stroke. Ignition then occurs and the cycle of operations just described is repeated.

Although but one specific embodiment of this invention has been herein shown and described, it will be understood that numerous details of the construction shown may be altered or omitted without departing from the spirit of this invention as defined by the following claims.

I claim:

1. The combination of an engine cylinder, a pumping cylinder, pistons in said cylinders, a fuel intake port in the wall of said engine cylinder, said pistons having passages therein adapted to connect said intake port with the pumping cylinder and adapted to be controlled by the relative movements of said pistons.

2. In an engine, the combination of an engine cylinder and a pumping cylinder, pistons in said cylinders, an exhaust passage through the pumping cylinder piston, and exhaust ports in the walls of both of said cylinders, said ports and passage being adapted to be brought into communication with the movement of said pumping piston.

3. In an engine, the combination of an engine cylinder, a pumping cylinder, pistons for said cylinders, an intake port in said engine cylinder, an exhaust port in said pumping cylinder at respectively different levels, three communicating ports between said cylinders, being respectively located at the levels of said intake and exhaust ports and at an intermediate level, each of said pistons having two annular passages in its periphery, a passage connecting the upper annular passage in one of said pistons with the space above said piston, and a second passage connecting the lower annular passage in the other of said pistons with the space above said other piston whereby both of said pistons will coöperate to control each of said inlet and exhaust ports.

4. An internal combustion engine, comprising an engine cylinder and a pumping cylinder, pistons operating in said cylinders, said cylinders having a plurality of communicating-ports between them, a fuel inlet port located in said engine cylinder and adapted to be controlled by said engine piston, an exhaust port located in said pumping cylinder and adapted to be controlled by said pumping piston, the engine cylinder piston having a recess adapted to register with said fuel inlet port, and one of said communicating-ports for admitting fuel into said pumping cylinder, and the pumping cylinder piston being adapted to control communication between said exhaust port and another of said communicating-ports for permitting the escape of burned gases from said engine cylinder.

5. An internal combustion engine, comprising an engine cylinder and a pumping cylinder, pistons in said cylinders, said cylinders being provided with a plurality of communicating ports adapted to be controlled by said pistons for opening communication between said cylinders, a fuel inlet port located in said engine cylinder substantially in alinement with one of said communicating-ports, and an exhaust port located in said pumping cylinders substantially in alinement with another of said communicating-ports, said pistons being each provided with a recess, one adapted to register 10 with said fuel inlet and said first mentioned communicating-port for admitting fuel into said pumping cylinder, and the other adapted to register with said exhaust port and said other communicating-port for permitting an escape of burned gases from said engine cylinder. 15
6. An internal combustion engine, comprising an engine cylinder and a pumping cylinder, pistons in said cylinders, said cylinders being provided with a plurality of communicating-ports adapted to be controlled by said pistons for opening communication between said cylinders, a fuel inlet port located in said engine cylinder substantially in alinement with the lowermost of said communicating-ports, and an exhaust port located in said pumping cylinders substantially in alinement with the uppermost of said communicating-ports, 20 said pistons being each provided with a recess, one adapted to register with said fuel inlet and said lowermost communicating-port for admitting fuel into said pumping cylinder, and the other adapted to register 25 with said exhaust port and said uppermost communicating-port for permitting an escape of burned gases from said engine cylinder. 30
7. An internal combustion engine, comprising an engine cylinder and a pumping cylinder, pistons in said cylinders, said cylinders being provided with a plurality of communicating-ports adapted to be controlled by said pistons, a fuel inlet port located in said engine cylinder substantially in alinement with one of said communicating-ports, an exhaust port located in said pumping cylinder substantially in alinement with another of said communicating-ports, 35 said engine piston being provided with a recess adapted to register with said fuel inlet and said first mentioned communicating-port, said pumping piston being provided with a recess adapted to register with 40 said first mentioned communicating-port and having a passage extending from said recess to the inner end of said piston, said pumping piston being also provided with a recess adapted to register with said exhaust port and said other communicating-port, 45 and having a passage extending from said recess to the inner end of said piston, said pumping piston being also provided with a recess adapted to register with said exhaust and upper communicating-ports, said lower recess being adapted to register with said fuel inlet and lower communicating-port, said upper recess being adapted to register with said intermediate communicating-port and having a passage extending therefrom to the inner end of said piston and opening into the engine cylinder, said pumping piston being also provided with upper and lower recesses, 50 said upper recess being adapted to register with said exhaust and upper communicating-ports, said lower recess being adapted to register in succession with said lower communicating-port and with said intermediate communicating-port, and said piston having a passage extending from said lower recess to the upper end of said piston and opening into the pumping cylinder, and means for causing a reciprocatory movement 55 of said pistons whereby there will successively occur simultaneous registration of the lower recess in said pistons with said lower communicating-port, then simultaneous registration of the lower recess in said pumping piston and the upper recess in said engine cylinder. 60
8. An internal combustion engine, comprising an engine cylinder and a pumping cylinder, pistons in said cylinders, said cylinders being provided with an upper, a lower, and an intermediate communicating-port, a fuel inlet port located in said engine cylinder substantially in alinement with said lower communicating-port, an exhaust located in said pumping cylinder substantially in alinement with said upper communicating-port, the engine piston being provided with an annular recess adapted to register with said fuel inlet and said lower communicating-port, the pumping piston being provided with a pair of annular recesses respectively adapted to register with said lower and intermediate communicating-ports and with said exhaust and upper communicating ports, 65 said engine piston being also provided with means affording communication between said intermediate communicating-port and the engine cylinder, and means connecting said pistons with a rotatable member whereby the recesses in said pistons will be caused to respectively register in succession with said respective ports. 70
9. An internal combustion engine, comprising an engine cylinder and a pumping cylinder, pistons in said cylinders, said cylinders being provided with an upper, a lower, and an intermediate communicating-port, a fuel inlet port located in said engine cylinder substantially in alinement with said lower communicating-port, an exhaust located in said pumping cylinder substantially in alinement with said upper communicating-port, said engine cylinder piston being provided with lower and upper recesses, said lower recess being adapted to register with said fuel inlet and lower communicating-port, said upper recess being adapted to register with said intermediate communicating-port and having a passage extending therefrom to the inner end of said piston and opening into the engine cylinder, said pumping piston being also provided with upper and lower recesses, 75 said upper recess being adapted to register with said exhaust and upper communicating-ports, said lower recess being adapted to register in succession with said lower communicating-port and with said intermediate communicating-port, and said piston having a passage extending from said lower recess to the upper end of said piston and opening into the pumping cylinder, and means for causing a reciprocatory movement of said pistons whereby there will successively occur simultaneous registration of the lower recess in said pistons with said lower communicating-port, then simultaneous registration of the lower recess in said pumping piston and the upper recess in said engine cylinder. 80
10. An internal combustion engine, comprising an engine cylinder and a pumping cylinder, pistons in said cylinders, said cylinders being provided with an upper, a lower, and an intermediate communicating-port, a fuel inlet port located in said engine cylinder substantially in alinement with said lower communicating-port, an exhaust located in said pumping cylinder substantially in alinement with said upper communicating-port, the engine piston being provided with an annular recess adapted to register with said fuel inlet and said lower communicating-port, the pumping piston being provided with a pair of annular recesses respectively adapted to register with said lower and intermediate communicating-ports and with said exhaust and upper communicating ports, 85 said engine piston being also provided with means affording communication between said intermediate communicating-port and the engine cylinder, and means connecting said pistons with a rotatable member whereby the recesses in said pistons will be caused to respectively register in succession with said respective ports. 90

gine piston with the intermediate communicating-port; and then the registration of the upper recess in said pumping piston with said exhaust and the upper communicating-port at the time the upper end of said engine piston is below said upper communicating-port.

Signed at Chicago this 2nd day of May 1913.
